UNITED STATES PATENT OFFICE.

ANDREW J. HENTSCHEL, OF SCHULENBURG, TEXAS.

BRIDLE.

1,132,182.

Specification of Letters Patent. Patented Mar. 16, 1915.

Application filed April 20, 1914. Serial No. 833,261.

To all whom it may concern:

Be it known that I, ANDREW J. HENTSCHEL, a citizen of the United States, residing at Schulenburg, in the county of Fayette, State of Texas, have invented certain new and useful Improvements in Bridles; and I do hereby declare the following to be a full, clear, and exact description of the invention, such as will enable others skilled in the art to which it appertains to make and use the same.

This is an improvement on my application, Serial No. 785,505, filed Aug. 19, 1913.

The present invention relates to a bridle and more particularly to a bridle wherein means for controlling a horse is provided.

An object of the invention is to provide a device which can be used either with or without the ordinary driving bit.

20 A further object of the invention is to provide a device wherein an unruly horse which cannot be controlled by the ordinary driving bit may be controlled.

25 A still further object of the invention is to provide a device by which a horse may be effectually guided.

With these and other objects in view, the present invention consists in the arrangement and combination of parts as herein 30 set forth.

Referring to the drawing; Figure 1 is a front elevation of my device. Fig. 2 is a sectional view on the line X—X of Fig. 1. Fig. 3 is a sectional view on the line Y—Y 35 of Fig. 1. Fig. 4 is a plan view of my device showing the controlling lever and operating mechanism therefor, in operative position.

Referring to the drawings by reference 40 characters wherein similar parts are indicated by similar characters, the device consists of a frame 1 of U-shape and adapted to fit the contour of a horse's nose. On the inside of this frame is a pad member 2 of any suitable material. Removably secured 45 by screws 1' to this frame at the front portion thereof is a small piece of spring metal 2' having an inwardly projecting prong 3' adapted to contact with the horse's nose if he pushes it forwardly. In the upper front 50 edge of said frame is a slot 3 to which a supporting strap 4 is adapted to be attached. Supporting straps 5 are attached to the rings 6 pivotally held on the rear ends of the 55 frame member. In the forward face of the said frame member is an opening 7 in which

are adapted to operate the lever members 8. These lever members are pivoted, as at 9, to the upper and lower clips 10 and on the inner ends of these levers are presser members 11 arranged to contact with the nostrils of a horse. The outer ends of these lever members are extended forwardly and thence curved rearwardly, as at 12. To the free ends of these rearwardly curved portions 12 are attached links 13 which links are attached at their free ends to the lever actuating mechanism. This actuating mechanism comprises tubular members 14 attached to the side of the frame 1 and extending longitudinally thereof. These tubular members are threaded internally at their rear ends and in these internally threaded portions are inserted set screws 15 having longitudinally extending apertures 16. In the other ends of these tubular members are 60 65 70 75 80 85 90 95 100 105 110 slidably arranged plugs 17 to which are attached the links 13. These members 17 are internally threaded, as at 18.

Extending through the set screws 15 are rods 19, screw threaded on their forward ends, as at 20, where they are adapted to engage the screw threads in the plug members 17. On the rear ends of the rods 19 are eye members 21 to which are adapted to be attached the reins 22.

When it is desired to operate the lever members and engage the nostrils of a horse by the inner ends thereof the reins 22 are pulled rearwardly through the rods 19, the links 13 and the levers 8, and the nostrils of the horse are engaged. In order that the said nostril engaging members may not be actuated too easily and that the pressure on the nostrils may be somewhat controlled by the device itself I provide springs 23 encircling the rods 19 within the tubes 14, and bearing at one end against the plugs 17 and at the other end against the set screws 15. The said springs normally tend to return the nostril 100 engaging members to inoperative position and may also be adjusted by means of the said set screws 15 so that their tension will be either materially increased or decreased. Thus if it is desirable to increase the tension it is done by screwing the said set screws 15 inwardly within the tubes 14. It is at times desirable to increase the tension of these springs so that a pull may be brought to bear upon the reins and the horse 110 guided without even actuating the lever members or when actuating them to such an

extent that the horse's respiration will not be interfered with.

In order to clamp the set screws 15 after being screwed into the ends of the tubes 14, 5 I have provided the said set screws with longitudinally extending slots 24 and in these slots are mounted leaf springs 25. These springs may be depressed below the surface of the threaded portions of the set 10 screws, while the set screws are being adjusted, but after the same have been adjusted, the springs are then released and bear against the threads of the tubular members 14, thus frictionally preventing the said set 15 screws from rotating.

I have provided further means whereby my device may be used merely for guiding a horse, and this means acts to lock the lever members in inoperative position. On the 20 set screws 15 are formed internal threads 26 and on the rear end of each rod is mounted a member 27 which is internally threaded and adapted to be adjusted upon the rod on the threads 28. This member 27 has an externally threaded shank 29 which is arranged to be screwed into engagement with the internal threads 26 on the set screws. When this is done the lever members will be 25 locked in operative position and the device may be used merely for guiding the horse. To again allow the lever members to be operated by a pull upon the driving reins it is only necessary to disengage the members 27 from the internal threads of the set screws 30 for then the presser members will be allowed to operate through the actuating rods.

Copies of this patent may be obtained for five cents each, by addressing the "Commissioner of Patents, Washington, D. C."

It may be thus seen that I have provided a device which may be used for controlling a horse which is absolutely uncontrollable by the ordinary driving bit, and I have further provided a device which may be used as a bitless bridle without employing the said controlling means. 40

I do not wish to be limited to the particular embodiment shown any further than is 45 necessary by the claims.

What is claimed is:—

1. A device of the class described comprising, a frame, levers pivoted to said frame, presser members on one end of each 50 of said levers, links connected to the other ends of said levers, operating rods connected to said links, spring means for holding said levers in inoperative position, tubular casings mounted on said frame and inclosing 55 said rods and said spring means, and means operatively connected to said casings for varying the tension of said spring means.

2. In a bridle, a frame constructed and arranged to bridge the nostrils of a horse, 60 levers pivoted thereto and arranged to engage the nostrils of the horse, means for operating said levers, spring means for returning said levers to inoperative positions, and means to vary the tension of said spring 65 means.

In testimony whereof, I affix my signature, in the presence of two witnesses.

ANDREW J. HENTSCHEL.
